SNOW VEHICLE

Joseph Diemond, Simsbury, and Leonard E. Greenberg,
West Hartford, Conn., assignors to Coleco Industries,
Inc., Hartford, Conn., a corporation of Connecticut

Filed Jan. 2, 1970, Ser. No. 20,748

Term of patent 14 years

Int. Cl. D21—03

U.S. Cl. D34—15

FIG. 1

FIG. 2

FIG. 3

FIG. 4

FIG. 5

FIG. 6

FIG. 7

FIG. 1 is a perspective view of a snow vehicle showing our design;

FIG. 2 is a plan view thereof;

FIG. 3 is a side elevational view thereof;

FIG. 4 is a bottom view thereof;

FIG. 5 is a front view thereof;

FIG. 6 is a rear view thereof; and

FIG. 7 is a fragmentary side elevational view thereof with the handle in an elevated operative position.

We claim:

An ornamental design for a snow vehicle, as shown.
